UNITED STATES PATENT OFFICE.

BEECHER C. HUTTO, OF PELION, SOUTH CAROLINA.

LAMP-CHIMNEY.

1,295,322.

Specification of Letters Patent.

Patented Feb. 25, 1919.

Application filed March 23, 1918. Serial No. 224,379.

To all whom it may concern:

Be it known that I, BEECHER C. HUTTO, a citizen of the United States, residing at Pelion, in the county of Lexington and State 5 of South Carolina, have invented certain new and useful Improvements in Lamp-Chimneys, of which the following is a specification, reference being had to the accompanying drawings.

- 10 This invention relates to an improved lamp chimney, and has for its primary object to provide improved means on the neck of the chimney for engagement by upstanding resilient arms on the lamp burner 15 whereby the chimney will be securely held in its applied position against accidental displacement, while at the same time the chimney may be easily and quickly removed when necessary.
- 20 It is also another object of the invention to provide the chimney with improved means whereby it is properly held in applied position, which is very simple in construction and will not add to the cost of 25 manufacture of the ordinary lamp chimney and which will also be highly efficient and reliable for the purpose in view.

With the above and other objects in view, the invention consists in the improved form 30 and construction of the several features of the lamp chimney as will be hereinafter more fully described, subsequently claimed and illustrated in the accompanying drawing in which similar reference characters 35 designate the corresponding parts throughout the several views, and wherein:—

Figure 1 is a side elevation of an ordinary hand lamp provided with my improved chimney;

40 Fig. 2 is an enlarged fragmentary vertical section; and

Fig. 3 is a section taken on the line 3—3 of Fig. 1.

Referring in detail to the drawing where- 45 in I have illustrated an ordinary hand lamp, 5 designates the lamp chimney having a neck portion 6 adapted to be seated in the usual manner at its lower edge upon the rim of the burner indicated at 7. The neck 6 of the chimney is provided intermediate of its ends with a continuous annular bead 8 having its upper side slightly inclined upwardly as at 9 and merging into the wall of the neck 6. The lower side of this bead 55 which likewise merges into the neck wall is at a relatively greater inclination with re-

spect to the horizontal plane of the bead 8 as shown at 10 and presents a gradual slope or incline in the wall of the neck 6 for engagement with the upper ends of the spring 60 arms 11 which are fixed at their lower ends to the burner 7. Each of these retaining arms for the lamp chimney, preferably three in number, is outwardly bent adjacent its upper end to provide a seat 12 for the bead 65 8, the terminal of the arm being outwardly bent or inclined as shown at 13.

In the application of the chimney to the lamp burner, the neck 6 is moved downwardly between the arms 11, and the lower 70 inclined side of the bead 8 engaging the outwardly disposed terminals 13 of said arms forces the arms outwardly until the lower edge of the neck 6 is seated on the rim of the burner and the bead 8 is disposed in a plane 75 below the ends 13 of the arms. The arms then immediately spring inwardly into clamping engagement upon the bead 8 which is received in the seats 12 of said arms. The lamp chimney is thus securely held or 80 retained in its applied position and its casual or accidental displacement and breakage obviated. The chimney may be readily removed when necessary by simply forcing the upper ends of the arms 11 outwardly 85 beyond the bead 8 on the neck of the chimney.

From the foregoing description taken in connection with the accompanying drawing, the construction and manner of operation of the device will be readily understood. The 90 bead 8 can be easily formed on the neck of the lamp chimney so that the chimney may be produced at substantially the same cost as the ordinary lamp chimney of this character. It will also be noted that the provision of this bead on the neck of the chimney does not in any manner interfere with the 95 quick and thorough cleaning of the surfaces of the chimney.

Having thus described my invention, what 100 I claim is:—

The combination with a lamp having a burner and a plurality of upstanding spring arms fixed to said burner, of a lamp chimney having a neck portion engageable between the spring arms and provided with a continuous outwardly projecting annular bead, the wall of the chimney being formed with a relatively long outwardly inclined portion constituting the lower side of the 105 bead and a relatively short inwardly and upwardly inclined portion constituting the up- 110

per side of said bead, each of the spring arms having an outwardly inclined portion terminating in a bend at the upper end thereof for engagement upon the upper side 5 of the bead, and said inclined portions of the arms being spaced from the lower side of said bead.

In testimony whereof I hereunto affix my signature in the presence of two witnesses.

BEECHER C. HUTTO.
